BENDABLE PRONG PAPER FASTENING CLIP

William E. Bassett, Woodbridge, Conn., assignor
to The W. E. Bassett Company, Derby, Conn.,
a corporation of Connecticut

Application April 7, 1951, Serial No. 219,806

1 Claim. (Cl. 24—153)

1

This invention relates to a fastening clip of the type comprising a bendable fastener which is struck from sheet material (preferably metal) and bent intermediate its length to provide two sections in an angular relation to each other and integrally connected, with one or more prongs on one section adapted to be forced, by pressing the two sections together, through the articles to be connected and locked to the other section to thus retain the fastener in closed position.

It is an object of this invention to provide an improved clip or fastener of the type indicated in which there is no danger of the pointed end of the prong pricking the fingers of the user in the setting operation or after being set, in which the fastener is automatically locked by the simple operation of pressing the angularly arranged side members together.

It is also an object to provide a device of the character indicated which may be used for easily and quickly securing together a plurality of sheets of paper or the like, and is particularly adapted for closing containers or candy bags of paper, cloth, cellophane or like material, or for attaching labels or clipping papers and so forth.

In general, the object is to provide a simple, cheap, easily manufactured fastener clip which is easy to use and is very effective in use.

In the drawings which show, for illustrative purposes only, a preferred form of the invention:

Fig. 1 is a perspective view of the fastener clip on an enlarged scale showing it in the normal condition ready for use;

Fig. 2 is a plan view of a finished strip in the flat before bending to the condition of Fig. 1;

Fig. 3 is a longitudinal section substantially on line 3—3 of Fig. 2;

Fig. 4 is a longitudinal central sectional view on a greatly enlarged scale showing the relationship of the parts just before the prong engages the opposed clip section;

Fig. 5 is a fragmentary view in elevation showing the fastener clip in closed or set position;

Fig. 6 is a fragmentary longitudinal section showing the clip in the closed or locked position, the section being substantially on line 6—6 of Fig. 5; and

Fig. 7 is a transverse section substantially on the line 7—7 of Fig. 5.

The fastening clip is stamped from sheet material which will be referred to herein as sheet metal of the proper gauge and also of the proper hardness and composition so that it readily may be bent to the proper form, and when forced or pressed to the securing or fastening position the

2

parts will be bent to perform their function and the device will be maintained in set or locked position.

The fastener blank comprises an oblong body portion 10 provided at one end with one or more prongs 11 and at the other end with one or more corresponding hoods 12 in general alignment with the prong or prongs 11. The blank is bent intermediate its length, as indicated in Fig. 1, 10 to form an angular shaped element comprising two sheet metal sections or body portions 13 and 14 integrally connected by the intermediate bend 15, the position of this bend being indicated by the dotted lines 15a in Fig. 2. To make the clip 15 more easily bendable along the line 15a, the cross-section may be reduced as by punching an opening 16 therein. The stiffness and rigidity of the sheet metal sections may be increased if desired by pressing a series of longitudinal ribs or beads 17 therein.

The pointed prong 11 is formed by lancing or slitting the metal of section 14 along the converging meeting lines or edges 18—18 and pressing the prong out from between the lance lines. 25 The prong near its base is preferably at right angles to the section 14 as indicated at 11'. Outwardly beyond the right angularly extending section 11' the prong is preferably straight or very slightly curved, as indicated at 19, and the tip 19' is slightly hooked over or bent relatively to the section 19. The tongue and particularly the hook end 19' is preferably slightly bent to concavo-convex transverse section, as indicated in Fig. 7, so as to give rigidity or stiffness, particularly to the hooked or bent over tip.

30 The hood 12 is formed in the section 13 by slitting the section 13 transversely, as indicated at 20, and then pressing out the metal into the general hood shape as shown. The pressing out of the metal to form the hood leaves an opening 40 through which the end 19' of the tongue may pass and engage and ride on the metal of the section 13 adjacent the slit 20. The inside of the hood is curved both transversely and longitudinally and acts as an anvil surface for the prong 11. The hood 12 is preferably curved rather gently longitudinally as at 23—24, and the part approaching the slit 20 is preferably hooked in on a sharper curvature at 25 corresponding more or less to the curvature of the prong 50 point 19'.

As shown particularly in Fig. 4, the prong 11, beyond the right angularly extending part 11', is inclined toward the hinge end 15 of the clip, and the hood 12 is positioned so that the prong 55 end 19' engages the inner camming surface of

the hood quite near the open end of the hood. When the sides 13-14 of the clip are pressed together, the prong tip 19' is cammed through the opening at the end of the hood and rests on the surface beyond the slit 20. The rounded cam surface and the camming curved edge 25 of the hood at the slit hold or lock the prong end 19' in the position shown in Figs. 5, 6 and 7. The main body of the prong is bent or formed by the inner surfaces of the hood into the form shown in Fig. 6, and the constant tendency is to hold the tip 19' in the locked position, as shown. The slightly hooked end 19' and the transverse curvature strengthen the prong so that the prong and curved hood hold or lock the prong end securely in the locking position shown.

When the fastener clip is to be used to clip parts together, such as sheets of paper, the clip in normal position shown in Fig. 5 is engaged over the edges of the sheets 26, indicated in Fig. 6, and the side sections 13 and 14 are pressed together between the thumb and finger. The prong 11 will pierce the sheets, and the fastener clip will lock together as heretofore described. During the operation of closing the fastener clip, there is no danger of the pointed end 19' of the prong 11 piercing or scratching the fingers. Also, as the prong is forced or locked tightly against the outer surface of the section 13 beyond the opening 22, and is tightly locked between this surface and the curved-in surface 25 of the hood, the point is protected so that there is no danger of its catching on the fingers or other articles after being set in the fastening position. Also, the prong is positively and definitely locked in the fastening position so that there is little danger that the clip will open up accidentally. It will be evident that coaction of the further inturned hook or curved wall 25 of the hood and the somewhat hooked or further bent end portion 19' of the pointed prong is an important feature in the operating and setting of this clip and one which prevents injury to the fingers of the user during the setting operation and definitely holds or locks the prong, and particularly its pointed free end, so that there is no danger of its causing injury

to or catching on other articles when in the locked or set position.

It will be clear that my improved fastener clip is cheap to manufacture, easy to use, safe, and exceedingly secure.

While the invention has been described in detail and one preferred form shown, it is to be understood that changes and modifications may be made within the scope of the claim.

I claim:

A bendable sheet metal fastener comprising a single piece bent between its ends to form two sections extending at an angle to each other and bendable further to locking position, one of said sections having a struck up pointed tongue extending toward the other section, said other section having a transverse slit therein and the metal at one side of said slit being struck up in the form of a hood providing a concave anvil surface to be engaged by said tongue, whereby said tongue will be cammed into locking position by said anvil surface when said sections are pressed toward each other to locking position, said tongue before being engaged by said hood and when said fastener is in normal open position having its base portion at substantially right angles to the section carrying said tongue, and said tongue beyond said base portion being inclined inwardly in the angle between the sections, and the sharp end of said tongue being further curved to further incline the point for the purpose set forth, said sharp end of said tongue being arched or curved transversely to present a convex surface both longitudinally and transversely to said anvil surface.
